DESIGN FOR A CARRIAGE FOR SUPPORTING AND PROPELLING A TOOL, SUCH AS A BLOWPIPE

Frank C. Geibig, Westfield, N. J., assignor to
Oxweld Acetylene Company, a corporation of
West Virginia

Application April 24, 1940, Serial No. 91,912

Term of patent 14 years

To all whom it may concern:

Be it known that I, Frank C. Geibig, a citizen
of the United States, residing at Westfield, in the
county of Union and State of New Jersey, have
invented a new, original, and ornamental Design
for a Carriage for Supporting and Propelling a
Tool, Such as a Blowpipe, of which the follow-
ing is a specification, reference being had to the
accompanying drawing, forming a part thereof.

In the drawing, Figs. 1 and 2 are respectively a
perspective view and a plan view of a Carriage
for suppor and propelling a tool, such as a blow-
pipe, illustrating my design.

I claim:

The ornamental design for a carriage for sup-
porting and propelling a tool, such as a blow-
pipe, substantially as shown.

FRANK C. GEIBIG.
